DETACHABLE POUR SPOUT

Alfred J. Gramp, Atlantic City, N. J.

Application April 23, 1941, Serial No. 389,979

3 Claims. (Cl. 221—23)

This invention relates to the dispensing of liquids and is more particularly concerned with the provision of a pour spout for use with liquid containers of the type of paint cans and the like.

Liquids, such as paint, syrup, lubricating oils, etc., are at present very largely distributed to the retail market in cans of rectangular cross-section which are provided with a more or less flat upper surface. Ordinarily a threaded boss is provided on the upper surface, this boss having an aperture defining flange in which a lid may be seated and frictionally held. Because of the fact that containers may be subjected to considerably rough treatment in shipment it is customary, as a safety measure, to provide, additional to the lid, a threaded cap fitting over the boss on the top of the can and serving to insure the maintenance of the frictionally held lid in position. Cans of this type when used require removal first of the threaded cap and then of the lid. Once this is done, the liquid within the container may be dispensed. However, the user of materials so packaged is hampered in the pouring or dispensing operation, the problems encountered being most prevalent when the container is full. Thus, the first pouring operation is likely to result in the spilling of a portion of the liquid down the side of the container because of the location of the pour opening about an inch in from the outside edge of the can, a condition made necessary by the machinery employed in can manufacture.

To overcome the difficulty outlined above a number of pour spouts have been devised. These, as broadly considered, may be classified in two groups; first, a type permanently attached to the receptacle and, second, one detachable therefrom. The chief advantage of the permanently attached type of pour spout is that it cannot become lost and, in manufacture, it may be located in such a way as to avoid interference with the positioning of the lid or other temporary cover. In the transportation and storage of such containers, however, difficulties are presented, for ordinarily such cans cannot be superimposed in shipment and as a consequence they will occupy more space than cans not so equipped. It will be readily recognized that additional space occupied in shipment is a matter of considerable importance and that the elimination of this waste space is desirable consistent with maintenance of the advantages inherent in the provision of a pour spout.

To overcome the disadvantages of the permanently attached type of pour spout and at the

same time to facilitate dispensing, considerable effort has been directed toward the provision of a satisfactorily constructed detachable pour spout. At present detachable pour spouts for use with cans or other receptacles having the threaded boss type dispensing opening include a pouring lip permanently attached to a threaded sleeve, which sleeve is adapted to surround the boss in replacement of the threaded cap with which the container is initially provided. Such an arrangement is economical and has some advantages. However, when the sleeve is screwed into position on the boss of a paint can or the like the lip of the pour spout may be disposed in only one pouring position, other positions being attainable only when the sleeve is partially unscrewed and thus loosened will not maintain its adjustment. To overcome the difficulty just recited, it was proposed to provide a paint can or the like with a pour spout having an annular flange, said flange to be held in position between a flange on the screw threaded sleeve and a flange on the boss of the can top. Thus, by loosening the sleeve, the pour spout could be directed to any desired position and so held while the sleeve was screwed down to the desired degree of tightness.

Difficulties are inherent in the structures described above for necessarily the threaded flange and its attached pour spout must be entirely removed from the can by unscrewing before the normal lid can be placed in position. Thus, the pour spout cannot be left in operative position during temporary storage of the material after it is in the hands of the retail consumer and subsequent to the first use thereof.

It is therefore an object of this invention to overcome all of the foregoing difficulties and to provide a detachable pour spout which may be conveniently directed into any pouring position and which may be quickly and easily detached from the container with which it is used.

According to this invention, temporary sealing means may be employed in conjunction with a container provided with a detachable pour spout without the detachment of the spout.

Another object of this invention is to provide a pour spout of simple construction which may be quickly and easily made of inexpensive and readily available materials. According to the teachings of this invention a pour spout of paper or like material may be provided, the construction being sufficiently strong for the intended purpose while rendering available the inherent advantage of printing for advertising purposes.

Other objects and advantages of this invention will be apparent upon consideration of the following detailed description thereof in conjunction with the attached drawing, wherein:

Figure 1 is a top plan view of a metallic receptacle provided with a detachable pour spout constructed according to this invention;

Figure 2 is a longitudinal sectional view taken along the lines 2—2 of Figure 1 illustrating a preferred form of this invention;

Figure 3 is a detailed view in section illustrating a modified form of this invention involving a novel type connection between the flange of a pour spout and the flange of its retaining sleeve; and

Figure 4 is a detailed view in section illustrating a still further modified form of this invention in which the retaining sleeve is provided with a groove in which an arcuate portion of the pour spout is seated for movement with respect thereto.

Referring to the drawing in greater detail and particularly to Figures 1 and 2 thereof, this invention is shown as applied to a paint can 10 having the usual threaded boss 11 provided with a flange 12 for the reception of a frictionally held cover 13. It should be noted that the flange of cover 13 is adapted to rest against but a portion of the flange 12 of boss 11. The remaining portion of the flange 12, that is, the portion directly adjacent the threaded area is, according to this invention, adapted to form a seat against which a flange 14 of a threaded sleeve 15 may rest. As illustrated, sleeve 15 is adapted to surround boss 11 in threaded engagement therewith. Thus, sleeve 15 may be screwed down causing its flange 14 to approach flange 12 of boss 11. Referring now to Figure 2 it will be seen that a flange 16 is disposed intermediate flanges 12 and 14. Flange 16 forms an integral part of pour spout 17 which includes a generally crescent shaped pouring lip 18 for the direction of liquid issuing from the aperture defined by flange 12 of the boss. Pouring lip 17 may be made of card stock or of molded paper or even of thin sheet metal. It is important, however, that the lip be made of a resilient material so that the base of the pouring lip may be circumferentially compressed to cause flange 16 to be withdrawn from its position between flange 14 of sleeve 15 and flange 12 of boss 11. This can be readily accomplished by slightly loosening sleeve 15, it being wholly unnecessary to remove sleeve 15 from engagement with boss 11. The pour spout as illustrated is of molded paper and includes on its upper edge a turned-down portion 19 which serves as a reinforcement. Around the base of the pouring lip a metallic element 20 such as any thin sheet metal may be disposed. This serves the function of protecting the paper against wear which would be caused by frictional contact with flanges 14 and 12. Since the paper pouring lip is provided it is evident that advertising indicia may be printed thereon without interference with its primary function.

When the detachable pour spout just described is placed into operation, the user of the liquid material contained within receptacle 10 will ordinarily first remove the threaded cap which, according to conventional practice, occupies the position of sleeve 15 in the drawing. With the threaded cap removed, sleeve 15 is then screwed to a position where flange 14 is spaced just slightly above flange 11. Thereafter the pour spout construction is gripped at its ends

and reduced circumferentially. In this condition flange 15 thereof is passed between flange 14 and flange 12. If the pour spout is then released it will spring into position so that the arcuate flange will contact flange 11 for the entire length of the former. Thereafter the pouring lip 17 is directed into any desired pouring position and is so held while sleeve 15 is screwed down to a locking position, at which time flange 16 of the pour spout will be tightly gripped between flanges 12 and 14. At this time, the operator may pry loose lid 13 and commence the use of the receptacle. After a suitable quantity of material has been dispensed, lid 13 may be replaced. 15 This can be done without any interference whatsoever with the pouring lip. If desired, however, sleeve 15 can be slightly loosened, and the pouring lip again squeezed to cause reduction of circumference, thus allowing disengagement of flange 16 from its position between flanges 12 and 14. It will be seen that the construction described permits the pouring spout to be directed in any desired position and that the pouring spout may be quickly and easily detached without the complete removal of its retaining sleeve.

Referring now to the modified form of the invention shown in Figure 3, it will be seen that most of the parts correspond to those shown in Figures 1 and 2. However, the arcuate flange on the pour spout 15, designated in Figure 3 as 20, is an upstanding one and is adapted to cooperate with a down-turned flange 21 provided on threaded sleeve 15. This arrangement is of advantage because it is quite evident that the original threaded cap, the top of which will normally overlie lid 13, may be used later as a sleeve it being necessary only to cut the top of the can leaving an inwardly extending annular flange around the top edge of the threaded portion. 30 This flange will be normally bent down to the position shown in Figure 3 as an incident to the cutting operation. Clearly, if cutting out of the top of the threaded cap is done in a manner to avoid bending of the resulting flange, such flange 35 may be subsequently bent to a position as shown in Figure 3 or may be used as shown in Figure 2. The operation of the embodiment of the invention shown in Figure 3 is in all respects similar to that described above in connection with Figures 1 and 2.

The distinguishing feature of the form of the invention shown in Figure 4 is that the sleeve 15 is provided, not with an annular flange as in the other illustrated forms of the invention, but with an overturned portion 22 defining a groove. Within this groove the lower edge portion 23 of pour spout 17 is inserted, the configuration of the inserted portion of the pour spout conforming to the configuration of the groove. As before, the portion of the pour spout subjected to wear is covered with metal 19. In the form of the invention illustrated in Figure 4 the pour spout 17 is not detachable from the boss 11 of can 10 except by the concurrent removal of sleeve 15. 40 However, the gripping arrangement does permit the pouring lip and sleeve 15 to be relatively rotatable so that the sleeve may be moved to any position of adjustment. By tightly compressing the portion of the pour spout which lies between flange 12 and the lower edge of the groove defining member 22 of sleeve 15 it is possible to firmly hold the pour spout in any selected position.

While several forms of this invention have been described above it will be recognized that many modifications are possible within the scope

of the appended claims. The term arcuate as used herein is intended to designate a curve of something less than 360°.

What is claimed is:

1. In a receptacle including a boss having an annular flange defining a central aperture, a sleeve adapted to contact and surround said boss said sleeve having an annular flange adapted to overlie and contact a portion of the flange of the boss, and a pour spout of resilient material including a lip portion and an arcuate flange extending for less than 360°, said flange being adapted to nest between the flanges of said boss and said sleeve to be held thereby.
2. In a receptacle including a boss having an annular flange defining a central aperture, a sleeve adapted to contact and surround said boss said sleeve having an annular flange adapted to overlie and contact a portion of the flange of the boss, and a pour spout of molded paper including a lip portion and an arcuate flange extending for

less than 360°, said flange being adapted to nest between the flanges of said boss and said sleeve to be held thereby, said arcuate flange portion being provided with a thin sheet metal cover.

5. In a receptacle including a threaded boss having an annular flange defining a central aperture and a sealing lid adapted to close said aperture the lid being provided with a flange overlying a part of the annular flange of the boss, a threaded sleeve adapted to surround said boss in threaded engagement therewith said sleeve having an annular flange adapted to overlie a portion of the flange of the boss which is not engaged by the flange of said lid, and a pour spout of resilient material including a lip portion and an arcuate flange adapted to nest between the flange of said boss and said sleeve, whereby both the lid and the pour spout are rendered individually detachable without removal of said sleeve while both may be used together.
